UNITED STATES PATENT OFFICE.

RICHARD R. BRUCKNER AND LAMPERT BEMELMANS, OF NEW YORK, N. Y.

WINDOW-CLEANING APPARATUS.

1,289,638.

Specification of Letters Patent. Patented Dec. 31, 1918.

Application filed October 20, 1917. Serial No. 197,616.

To all whom it may concern:

Be it known that we, RICHARD R. BRUCKNER, a subject of the German Emperor, and LAMPERT BEMELMANS, a citizen of the United States, both residents of the city of New York, borough of Manhattan, in the county and State of New York, have invented a new and Improved Window-Cleaning Apparatus, of which the following is a full, clear, and exact description.

Among the principal objects which the present invention has in view are: to lessen the labor in cleaning windows; to avoid the necessity of the washer assuming a position outside the window being washed; to provide means for removing the soil in the corners of the windows; to provide means for automatically regulating the pressure on the window panes; and to provide means for rapidly securing the washing element to the apparatus.

Drawings.

Figure 1 is a side view of a cleaning apparatus constructed and arranged in accordance with the present invention, the apparatus being shown in conjunction with and in operative relation to a window sash;

Fig. 2 is an edge view of the cleaner;

Fig. 3 is a side view of the same;

Fig. 4 is a longitudinal section on an enlarged scale of the mop holder with which the invention is provided, the section being taken as on the line 4-4 in Fig. 2;

Fig. 5 is a side view of the apparatus, showing the same as inactively disposed or ready for storage.

Description.

As seen in the drawings, the apparatus has two mop holding frames, each frame consisting of a sheet iron triangular back 10. As seen best in Figs. 2 and 4 of the drawings, flanges 11 extend on each side of the triangular back. The back 10 is provided with hinge ears 12, through which in service a cotter pin 13 is passed. Between the ears 13, the perforated foot 14 is placed. The foot 14, as seen best in Fig. 4 of the drawings, has a curved under surface terminating in a toe 15. This arrangement permits the mop frame to rock on the cotter pin 13, so that the movement of the resilient bow arm 16 neither jams nor relieves the pressure between the pad and the surface of the window pane 17.

As seen best in Figs. 4 and 5, a hinge knuckle 18 is formed integral with the frame 10. The knuckle 18 is provided to pivot the spring frame 19, which holds the rubbing cloth or pad 20 on the frame 10. The frame 19 is contractible, the two sides being each provided with upstanding tips 21. When the tips 21 are pressed together, the body of the frame 19 is at liberty to pass within the contracted upper edges of the flanges 11. When the tips 21 are released, the frame 19 if adjacent the body of the back 10, springs under the overhanging flanges 11. If the edge of the rubbing cloth 20 be arranged to overlie the flanges 11, the frame will press the same under the said flanges, with the result that the cloth is held firmly in position.

One of the backs 10 is secured to the arm 16. The other of the backs is similarly secured to a rocking arm 22. The arm 22 has a hand-grip 23 and is pivotally connected by means of a pin 24 with the bow arm 16. It will be understood that the cloth 20 may be adjusted or removed from the back 10 either while the back is attached to the arm 16 or 22, or when it is removed therefrom.

When the cleaner is to be adjusted to its work, the operator moves the hand-grip 23 and the rocking arm 22 connected therewith, to the position shown by broken lines in Fig. 1 of the drawings. The rubbing cloth 20 and backs 10 supporting the same are then separated sufficiently to permit the passing between the same of the stile of the rail 25 of the window sash. The cloths 20 being disposed at opposite sides of the pane 17, the operator then moves the grip 23 and arm 22, until the two cloths or pads close on the said pane. In this position, the grip 23 stands slightly away from the bow arm 16. By contracting the hand enfolding the grip 23 and adjacent portion of the arm 16, the cloths 20 are forced firmly into contact with the opposite surfaces of the pane 17.

It is obvious that when full pressure required to draw the grip 23 and arm 16 together, has been applied, the maximum pressure imposed upon the cloths 20 equals the spring of the arm 16.

Having thus adjusted the cloths and supporting structure therefor, the operator passes the cloths over the pane 17, both cloths operating at opposite sides of the pane simultaneously. It will be observed that the back 10 being triangular in shape,

the rubbing pad formed by the cloths 20 is also triangular. This permits the introduction of the resultant pad into the corners of the window sash.

5 When it becomes necessary to renew or change the cloths 20, this may be done by releasing the grip 23 to rock the short arm 22 and separate the cloths 20 from the pane 17. The apparatus is then removed from op-
10 erative relation to the pane 17, the frames 19 are contracted and lifted out of engagement with the cloths 20 and the flanges 11 of the backs 10. The old cloths may then be removed and new ones substituted.

15

Claim.

An apparatus as characterized comprising a plurality of mop holders; a resilient

bow handle pivotally supporting one of said mop holders, said bow handle having relatively long and short extensions; a short arm complementary to the short extension of said bow handle, the combined length of said short arm and short extension being equal to the long extension of said bow handle, 25 said arm being pivotally connected with one of said holders; and a hand grip rigidly attached to said short arm and pivotally attached to said short extension, said grip being channeled to receive the adjacent portions of said short extension and short arm to connect the same whereby the ends of said long extension and said short arm may be pressed together manually.

RICHARD R. BRUCKNER.
LAMPERT BEMELMANS.
